(57) **CLAIM**

I claim the ornamental design for a telescoping clip-on reading light, as shown and described.

DESCRIPTION

FIG. 1 is a left side view of the telescoping clip-on reading light showing my new design having a telescoping arm with a pivoting light at its end fully extended;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a rear view thereof; and,

FIG. 8 is a perspective view of the telescoping clip-on reading light with the telescoping arm and the light positioned for storage.
